(57) **CLAIM**

The ornamental design for a vehicle ladder, as shown and described.

DESCRIPTION

FIG. 1 is a front perspective view of the vehicle ladder of my new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a front elevation view of the vehicle ladder provided relative to a vehicle.

The broken lines on the vehicle ladder depict portions of the vehicle ladder that form no part of the claimed design. The broken lines illustrating a vehicle in FIG. 8 depict environmental structure that forms no part of the claimed design.

1 Claim, 7 Drawing Sheets
